UNITED STATES PATENT OFFICE.

J BIRCHARD GREEN, OF CHICAGO, ILLINOIS.

PROCESS AND MACHINE FOR DRAWING WIRE.

Application filed August 6, 1925. Serial No. 48,465.

In the manufacture of wire by the methods and means heretofore employed, it has not been practicable to draw the wire at a high rate of speed, since, with those machines which operate but one pass at a time, the first pass and each of the subsequent passes must be drawn slowly or the wire will tangle and break as it leaves the take-off swift or reel, and, with those machines which operate all of the passes in continuous sequence, the first pass must be drawn slowly to prevent the wire from tangling as it leaves the swift and the subsequent passes can only be stepped up in speed over the first pass to the extent to which the wire is lengthened as a result of the preceding passes. It is quite desirable, however, that the wire be drawn at a high rate of speed after the first pass because the coefficient of the friction involved in the drawing varies inversely with the speed at which the wire is drawn, and, if the wire be drawn at a high rate of speed, not only is production to that extent increased, but the tension on the wire is reduced, the liability of breakage is minimized and the wear on the dies is lessened.

The principal object of the invention is to provide a machine with which wire may be drawn at a high rate of speed without liability of tangling and consequent breakage.

Another object is to provide a machine of the character described with which all of the necessary wire drawing passes may be effected in rapid sequence with the wire threaded through but one die at a time and moving first in one direction and then in the other.

Other objects and advantages will be evident upon a full comprehension of the novel construction, arrangement and operation of the machine.

The machine comprises essentially two wire carrying bobbins which are arranged on opposite sides of the wire drawing die and are connectible alternately with a power source for rotation, whereby the wire, after being drawn slowly through the die from a swift or reel and wound onto one bobbin, may be drawn rapidly in the reverse direction through a smaller die and wound onto the other bobbin, then drawn rapidly in the reverse direction through a still smaller die and wound back onto the first bobbin, and so on, the wire being drawn back and forth

rapidly from one bobbin to the other until the wire has been reduced to the desired size.

In order that the invention may be readily understood, one embodiment of the same is set forth in the accompanying drawing and following description, but, as will be appreciated by those skilled in the art, the invention is also susceptible of embodiment in other variously modified forms coming equally within the comprehensive scope of the claims.

In the drawing:

Fig. 1 is a side elevation of a machine embodying the invention;

Fig. 2 is a vertical section through one of the two duplicate wire drawing units of the machine, taken on the line 2—2 of Fig. 1; and

Fig. 3 is a horizontal section through one of the units, taken on the line 3—3 of Fig. 2.

The machine illustrated in the drawings includes two wire carrying bobbins 10 and 11 which are arranged on opposite sides of a wire drawing die 12. The bobbins, together with their associated mechanisms, are substantially duplicates of each other, and the following description of one will therefore suffice for both.

Each bobbin is detachably secured to a horizontal shaft 13 which is journalled within and projects from one side of a supporting frame 14. The shaft 13 is arranged in alignment with a continuously rotating shaft 15 which is operated from a vertical shaft 16, and the shaft 16 is rotated from a horizontal shaft 17 which is preferably common to the driving mechanisms of both bobbins.

It is desirable that the shaft 13, with its associated bobbin, have a slow or reduced driving connection with the shaft 15 under certain operating conditions; that it have a fast or one-to-one driving connection with the shaft 15 under other conditions; and that it be free to idle relative to the shaft 15 under still other conditions. While the connections mentioned may obviously be effected in a great many different ways, one simple instrumentality consists of a double faced clutch member 18 which is splined to the shaft 13 and is shiftable axially thereof, being movable in one direction into driving engagement with a clutch member 19 which is secured to the shaft 15, and being movable in the other direction into driving engagement with a clutch member 20 which is freely journalled on the shaft 13 and is connected by

gears 21 to a countershaft 22 which is in turn connected by reduction gears 23 to the shaft 15. When the clutch member 18 is out of engagement with both clutch members 19 and 20, the shaft 13, with its associated bobbin, is disconnected from the driving means and is free to rotate independently thereof. The clutch member 18 may be shifted into or out of any one of the three positions of the same by means of a conveniently located control lever 24 which is connected with the member through a pivoted shifting yoke 25 and an intermediate link 26.

It is desirable that the wire be wound onto or off of each bobbin helically in layers. While this may be accomplished equally well either by reciprocating the bobbin or by reciprocating a wire guide in advance of the bobbin, a simple means for the purpose consists of a guide 27 which is slidably mounted on a horizontal rod 28 in front of the bobbin and is horizontally reciprocated thereon by a blade 29 which extends from the guide into one of two intersecting and end connected helical grooves in a shaft 30 below the rod 28. The shaft 30 is connected by gears 31 to the shaft 13 on which the bobbin is secured, and, when the shaft 30 is rotated by the movement of the shaft 13, the guide 27 will be caused to travel from one side of the bobbin to the other at a speed proportionate to the speed of rotation of the bobbin, irrespective of whether the bobbin is serving as the receiving element for the wire and is being driven or whether it is serving as the take-off element and is merely idling.

Each bobbin preferably has in association therewith an ordinary wire drawing block 32. The block 32 may be detachably secured to a vertically extending shaft which is journaled in and projects from the top of the supporting frame 14 in alignment with the previously described shaft 16. The shaft 33, with its associated block, may be connected with the shaft 16 by means of a clutch member 34 which is splined to the shaft 33 and is movable into engagement with a clutch member 35 which is secured to the upper end of the shaft 16. The clutch member 34 may be moved into engagement with the clutch member 35 by means of a foot treadle 36 which is connected with the member 35 through a pivot shift yoke 37 and an intermediate link 38.

The die 12, which may be any one in the usual series of interchangeable reducing dies, is rigidly carried in a die box 39 which is mounted on a supporting frame 40, and the wire being drawn is trained over suitable guides 41 which are mounted on the frame 40 on opposite sides of the die.

If it is desired that the wire be what is known as a "wet drawn" product, each bobbin may have in association therewith a small tank 42 which is filled with the usual liquid

and is movable below the bobbin from a lowered or inoperative position to a raised position wherein the lower part of the bobbin with the wire thereon is immersed in the liquid. The tank 42 may be supported in its raised or lowered positions by any suitable means, such as a downwardly turned lip 43 on the upper edge of the tank which is adapted to hook into either one of two vertically spaced slots in an adjacent portion of the frame 14.

The machine is intended to be operated as follows:

One end of the wire to be drawn is threaded through the die 12 and is clamped to a flexible connector which extends through the guides 41 and 27 to one of the bobbins. Then the clutch controlling the rotation of the bobbin to which the wire is thus connected is thrown in to cause the bobbin to rotate at a slow speed, and the wire is as a consequence drawn slowly through the die from the swift or reel on which it was initially positioned and wound helically in layers on the bobbin.

At the completion of the first pass, the clutch is thrown into neutral and the end of the wire last through the die is rethreaded in the opposite direction through a substitute die of smaller size and is clamped to another flexible connector which extends through the other guides 41 and 27 to the other of the bobbins. Then the clutch controlling the rotation of that bobbin is thrown in to cause the bobbin to rotate at a high speed—this being possible because the wire is being unwound methodically from the other bobbin and will not tangle—and the wire is as a consequence drawn rapidly through the die in the reverse direction, being unwound off of one bobbin and wound on to the other. This is repeated for each succeeding pass with the exception of the last, the wire being drawn rapidly first in one direction and then in the other and being transferred from one of the bobbins to the other during the drawing.

At the commencement of the last pass, the end of the wire last through the die is connected to the block adjacent the empty bobbin, and the clutch controlling the rotation of that block is thrown in and the wire is wound rapidly onto the block in a readily removable coil.

If it is desired that the wire be wet drawn, it is only necessary during each of the several drawing passes, to raise the tank 42 under the receiving bobbin and lower the tank under the take-off bobbin.

In addition to the advantages of the machine which have already been referred to, it may be mentioned that the manner in which the wire is drawn by the machine, first in one direction and then in the other, tends to heal incipient fractures in the wire, since tension fractures in drawn wire assume

a conical form in the direction of pull, and constant reversal of the direction to pull serves to break up the development of such fractures. The decrease in wear on the die 5 permits of drawing greater lengths of wire with better maintenance of accuracy than heretofore attainable. It is not necessary to strip blocks between each pass, and the wire does not have to be lifted except at the start 10 and finish of the several passes. Furthermore, while the passes are made in rapid sequence, only one pass is drawn at a time, so that if the wire does break only a single operation is interrupted and but one rethreading is required. This feature alone marks a 15 substantial improvement over the multiple pass machines heretofore employed, since in the latter machines, the speed of operation is limited to the necessarily slow speed of the initial pass of stock taken from swift or 20 reel, and, if the wire breaks at any pass, it shuts down all of the passes and requires rethreading of all of the dies.

I claim:

25 1. A wire drawing machine, comprising a die for reducing a wire passed therethrough, two rotatable bobbins positioned on opposite sides of the die for carrying the wire before and after it is passed through the die in either direction, means for causing the wire to wind helically in layers on either bobbin upon rotation of the same in one direction, two rotatable blocks 30 also positioned on opposite sides of the die for drawing the wire into a removable coil on the last pass, and means for rotating either bobbin or either block.

into a removable coil on the last pass, and 35 means for transmitting power to either bobbin or either block to effect rotation of either bobbin at low speed on the first pass and at high speed on the subsequent passes and rotation of either block at high speed on the 40 last pass.

2. In a wire drawing machine, the combination with a die for reducing a wire passed therethrough, of two rotatable bobbins positioned on opposite sides of the die for carrying the wire before and after it is passed through the die in either direction, two rotatable blocks also positioned on opposite sides of the die for drawing the wire into a removable coil on the last pass, and means for 45 rotating either bobbin or either block.

3. In a wire drawing machine, the combination with a die for reducing a wire passed therethrough, of two rotatable bobbins positioned on opposite sides of the die for carrying the wire before and after it is passed through the die in either direction, means for causing the wire to wind helically in layers on either bobbin upon rotation of the same in one direction, two rotatable blocks 55 also positioned on opposite sides of the die for drawing the wire into a removable coil on the last pass, and means for rotating either bobbin or either block.

In testimony whereof I have hereunto subscribed my name.

J BIRCHARD GREEN.
